UNITED STATES PATENT OFFICE

STEPHAN KRAFT, OF VIENNA, AUSTRIA

PORTFOLIO

Application filed November 28, 1927, Serial No. 236,321, and in Austria October 26, 1926.

This invention relates to portfolios and has for its object the provision of novel means by which drawings, textile fabrics and other flat objects may be kept without creasing 5 in proper position enclosed in a nearly dust proof casing.

Briefly stated, the portfolio of the invention comprises alternate stiff panels and flexible strips, a swingably mounted frame at 10 one end to start winding the article on, end pieces attached to the panels and strips to space them apart as the portfolio is rolled up. This portfolio, when folded into casing form, is a flat parallelepipedal form with two 15 of its longitudinal surfaces covered by the flexible strips.

In the accompanying drawings:

Fig. 1 is a perspective view of the portfolio when open or unfolded.

Fig. 2 is a perspective view of the portfolio rolled up to form a case, this figure being drawn on an enlarged scale as compared with the scale of Fig. 1.

The portfolio is composed of panels 1, 2, 25 3 and 4 made of paper, wood, metal or any other suitable stiff material and connected by strips 5, 6 and 7 of flexible material as, for instance, cloth or leather.

In order to prevent the entry of dust and 30 in order to space the panels 1, 2, 3 and 4 apart when the portfolio is folded, end pieces 8 to 16, preferably of wood, are secured to the ends of the panels 1, 2, 3 and 4. The end pieces 8 and 16 of the panel 1 each has one 35 end projecting beyond the free edge of said panel, and a frame comprising a pair of rolls of paper 17 and 18 connected at their ends by arms 19 and 20 is mounted to rock between said projecting ends. A bolt 21 extending 40 through the projecting ends of the end pieces 8 and 16, the arms 19 and 20, and axially through the roll 17, serves to pivotally connect said frame to the end pieces 8 and 16, so that said frame may be folded against 45 or away from the panel. The roll 17 may be fixed and the bridges 19 and 20 may turn directly around the bolts 21 as their axes, which, in certain cases, may be shifted towards the roll 18.

To make the dust-proof closure a perfect

one and to assist in holding the portfolio together when closed to form a case, the end pieces 8 and 16 are each provided with a tongue 22 and the end pieces 9 and 15 are each provided with a corresponding groove 23 the 55 respective tongues and grooves engaging with each other when the portfolio is closed. Also at the free edges of the flexible strips 6 and 7, flexible end pieces 24—27, made, for instance, of felt or the like, are mounted, closely fitting to the end pieces 8, 9, 15 and 16 when the portfolio is closed.

The portfolio consists at least, of three parts to produce a proper casing, and to facilitate the safe retention of large drawings, and the like at one and the same time, the present arrangement effecting economy in storage. If the portfolio is made of canvas, leather, or the like, it is necessary to construct the panels 3 and 4 of a stiff material, 70 so that the portfolio, when closed to form a case, will retain its box-like shape.

In order to make use of the portfolio for inclosing and holding drawings or other flat objects, it is opened and spread over a table 75 and one end of the drawings is inserted under the swingably mounted frame, which frame is previously lifted to a certain angle and then restored to its original position. The portfolio with the drawings is then wound on 80 from the right to the left, as viewed in Fig. 1, beginning with the frame as the innermost part or core, the last panel 4 and opposite panel 3 finally forming the flat portions of the cover while the approximately semicylindrical parts are formed by the flexible strips. The ends are closed by the end pieces 85 engaging with each other through their tongues and grooves.

What I claim is:

1. A portfolio comprising a flexible wrapping member composed of alternate plane stiff and flexible sections, means carried by one of the end sections for securing thereto an end of the object to be encased and also 95 serving as a support for said object to be wound within the wrapping member, and co-operating members carried by certain of the sections for closing the ends of the portfolio when folded.

2. A portfolio according to claim 1, wherein in the article-securing means carried by one of the end sections includes means forming a core on which the wrapping member and the article carried thereby may be wound.
3. A portfolio according to claim 1 wherein in said object-securing means is composed of two spaced longitudinal members and two bridges connecting said members, said means being mounted to swing on an axis coaxially with one of said members.
4. A portfolio according to claim 1 in which the end members comprise rigid pieces attached to the stiff sections and flexible pieces attached to the flexible sections.
5. A portfolio according to claim 1 in which the end members include rigid pieces provided with complementary tongues and grooves to form a tight joint when the portfolio is closed.
6. A portfolio comprising a covering member composed of alternate stiff and flexible panels, and a frame attached to one end of the covering member and foldable inwardly and upon which the covering member may be wound, said frame consisting of two spaced round members and two arms connecting one member to the other, said arms being connected to the covering member to permit the frame to be swung relatively to the covering member, rigid end pieces attached to the stiff panels and flexible end pieces attached to the flexible panels, and complementary inter-engaging means carried by the rigid end pieces.

In testimony whereof I have hereunto set my hand.

STEPHAN KRAFT.
